UNITED STATES PATENT OFFICE.

PERCY GORDON ECKERSLEY DANIEL, OF CLEVEDON, ENGLAND.

GOLF-CLUB AND THE LIKE.

1,167,387.

Specification of Letters Patent.

Patented Jan. 11, 1916.

Application filed November 1, 1913. Serial No. 798,634.

To all whom it may concern:

Be it known that I, PERCY GORDON ECKERSLEY DANIEL, a subject of the King of Great Britain and Ireland, residing at Eckersley, Clevedon, in the county of Somerset, England, have invented certain new and useful Improvements in Golf-Clubs and the like, of which the following is a specification.

10 This invention relates to clubs, sticks and like implements for golf and other purposes wherein means are provided whereby the weight or balance or both of the club or the like may be varied to suit the requirements 15 of the user.

The object of the present invention is to provide effectively for the accommodation of an adjustable weight or weights or a weight or weights of varying magnitude so that the 20 effective weight can be adjusted as required to effect a change of weight or balance of the club or the like, and especially to provide against any chance of the weight or weights shifting or shaking about when in 25 use. I have found that especially in the case of golf clubs which of course suffer severe shocks when in use, a weight or weights may become loose unless very firmly held in place.

30 Reference will now be made to the accompanying drawings which illustrate the preferred mode of carrying the invention into effect in connection with the head of a golf club of the kind commonly used for "driving."

Figure 1 is a sectional view of the club head taken on the line 1-1 of Fig. 2. Fig. 2 is a rear view of the club head. Fig. 3 is a side view of the socket provided in the 40 club head and with the cap removed. Fig. 4 is a sectional view of said socket taken on the line 4-4 of Fig. 3; Fig. 5 is a sectional view of the cap for the socket; Fig. 6 is a side view of a solid weight for use in the 45 socket, that shown in Fig. 1 being hollow. Fig. 7 is an end view of the weight shown in Fig. 6; while Fig. 8 illustrates how the socket member may be attached to the end of the shaft of a golf club, or the like. Fig. 50 9 is a similar view to Fig. 1 but showing a modified form of weighting means.

In the drawings, *a* represents the club head which in the drawings is shown as an ordinary wooden driver head, *b* represents a recess bored in the head; this recess in the construction shown being placed substan-

tially centrally and in the line of flight of the head. It may at once be mentioned however, that I do not limit myself to the position of the recess, since this may vary with the form of club. For example the recess may be provided parallel to the face of the head, such an arrangement being useful for narrow heads such as the heads of putters. Within the recess a socket *c* preferably made of some non-corrodible metal, is fitted. The base of the socket is provided with an aperture to receive a screw as shown, and in order to avoid any chance of the socket turning around when in place a lug or lugs *d* may be provided as shown to engage a suitable recess or recesses in the head. I may even employ a square or rectangular socket to fit in a correspondingly shaped recess in the head.

The socket *c* is adapted to receive weights *e* of varying magnitude consisting in the construction illustrated of a cylindrical mass of brass or other metal of a size to fit snugly in the hollow of the socket. These weights are preferably of a single length so as to fill the hollow of the socket, and in order that weights of varying magnitude are provided they are mostly bored out to a greater or less extent so as to be partially hollow, as clearly shown in Fig. 1. The maximum weight will of course be solid as shown in Figs. 6 and 7. It will thus be seen that a set of weights may be provided of varying magnitude any one of which may be employed in the socket as desired.

In order that the weights may be easily removed, a small recess *f* consisting of two short borings at right angles may be provided at one or both ends, as clearly shown in Figs. 6 and 7. Such a recess may accommodate a bent piece of wire to extract the weight.

In order to keep the weights in place in the socket a cap *g* is provided which is adapted to screw upon the end of the socket as shown. It will also be seen that a number of slits are formed in the wall of the socket and further that the screw-threaded portions of the socket and cap are tapered slightly. Hence when the cap is screwed home upon the socket, the wall of the latter where it is slotted will be compressed slightly, to grip the weight which is being employed and prevent its shaking about. To provide a further safeguard against risk of movement of the weight within the socket,

the wall of the latter may be cut at one or more places to form a tongue or tongues as shown at *h*, the ends of which are bent inwardly slightly to engage the weight within 5 the socket. These tongues will yield slightly when the weight is inserted and tend to keep the same stationary. If, however, the weights are made a good sliding fit in the socket there should be no real necessity 10 for this extra safeguard, though this method may be adopted if desired in place of the tapered threaded portion.

The end of the cap *g* is preferably nicely rounded or shaped to follow the contour of 15 the surface of the head, and in order that it may be turned with a suitable tool, a slot *i* is provided as shown.

While the form of weights already described is the one preferred, yet in place of 20 single weights of varying magnitude I may employ a number of small weights in the socket at the same time as shown at *e*³ in Fig. 9, more or less of these weights being employed as desired. In this case the small 25 weights preferably consist of disks of metal of a size to fit snugly the aperture in the socket. Obviously to alter the weight of the club head or the like either some disks are added or taken away. In order to avoid 30 any chance of the disks rattling about, dummy disks *e*² of some relatively light but firm material such as aluminium, wood or ebonite may be employed to take the place of those weights which have been removed.

35 By providing dummy disks as just stated the actual weights may be concentrated in any desired position in the hole so that the balance of the head may be varied. For instance some dummy disks may first be 40 inserted and then the real weights inserted behind, thus tending to bring the center of gravity of the head farther back, and vice versa. In Fig. 9 the heavy disks are shown as arranged between dummy disks *e*². An 45 alteration of the position of the center of gravity will also be effected with the form of weight shown in Fig. 1 according to which end faces the face of the club, since the solid end of the weight will of course, 50 be the heavier. Weights may therefore be constructed so that their weight is concentrated at any part of their length desired by boring them from both ends to a greater or less extent.

55 Instead of or in addition to the weights in the head of the club I may also provide accommodation for a similar arrangement of weights in the handle or shaft of the club. For instance a hole may be made in 60 the handle in the direction of the axis thereof for containing weights as in the case of the head of the club. By altering the weight of the handle in this manner a marked difference in the balance of the club may be 65 effected. In view however, of the rather

small diameter of most club handles, where it is desired to provide accommodation in connection with the handle or shaft for a weight or weights I preferably adopt the arrangement shown in Fig. 8. That is to 70 say I attach a socket member *c* similar to that already described, to the end of the handle as shown, instead of placing the socket member within a recess in the handle.

75 Various changes may be made in the details of construction, for instance more than one recess may be provided for containing the weight or weights in which case the total weight in each recess may be less than if only one recess be employed. The dotted 80 circles in Fig. 2 indicate how two recesses may be arranged side by side. Further it is not essential to employ a separate socket portion for the weight or weights, especially where the part of the club or the 85 like to which the invention is applied is of metal.

It is also to be distinctly understood that the invention may be applied to any golf club so long as there is room for the accommodation of the weight or weights, and further the invention may be applied to other clubs, sticks or implements as for example, to cricket bats, croquet mallets, tennis rackets, hockey and polo sticks, and also to 95 billiard cues. In the latter case the weight or weights would be accommodated in the manner described in the butt end of the cue. The arrangement shown in Fig. 8 may be conveniently adopted for billiard cues, 100 the socket member *c* being attached to the butt end of the cue.

Having described the invention what I claim as new and desire to secure by Letters Patent is:—

105 1. A club, stick or like implement for golf or other purposes, weighting means therefor whereby the weight or balance or both may be varied, means for retaining the weighting means in place, and means movable against the side or sides of said weighting means so as to prevent the said weighting means from shifting when the implement is in use.

110 2. A club, stick or like implement for golf or other purposes, a recess therein, weighting means in said recess, means for closing the recess, and means movable against said weighting means so as to bring lateral pressure to bear thereon to secure the weighting 115 means in place.

120 3. A club, stick or like implement for golf or other purposes having a head, a socket member carried thereby having its axis in the line of flight of the head, weighting means for said socket member and means for bringing lateral pressure to bear on 125 said weighting means.

130 4. A club, stick or like implement for golf or other purposes, a socket member attached

thereto and open at one end, weighting means in said socket member, means for closing the open end of said socket member and means for bringing lateral pressure to bear upon said weighting means.

5. Means for varying the weight or balance or both of clubs, sticks or the like for golf or other purposes, comprising a socket member, means for closing said socket member, weighting means adapted to be contained therein, and means for contracting the socket member against the weighting means therein.

10. Means for varying the weight or balance or both of clubs, sticks or the like for golf or other purposes, comprising a socket member open at one end, weighting means therein, means for closing the open end of the receptacle to prevent longitudinal movement of the weighting means, and means for bringing lateral pressure to bear upon said weighting means.

15. Means for varying the weight or balance or both of clubs, sticks or the like for golf or other purposes, comprising a socket member, weighting means adapted to be contained therein, slots in the wall of the socket member near its open end, a screwed cap for closing said open end, and threads on the socket member for engagement by the threads of the cap, the screw threaded portions of the cap and socket member being tapered, whereby when the cap is screwed upon the socket member, the slotted wall thereof is contracted upon the weighting means.

20. Means for varying the weight or bal-

ance or both of clubs, sticks or the like for golf or other purposes, comprising a socket member, means for closing said socket member, weights of varying magnitude but equal exterior dimensions any of which may be placed within the said socket member, and means for retaining the said weights in place by bringing lateral pressure to bear there- 40 on when within the socket member.

25. Means for varying the weight or balance or both of clubs, sticks or the like for golf or other purposes, comprising a cylindrical socket member, means for attaching 50 the said socket member to the club, stick or the like, means for closing said socket member, means for preventing rotation of the said socket member, weighting means adapted to be carried within the said socket member, and means for bringing lateral pressure to bear upon said weighting means when in place.

30. Means for varying the weight or balance or both of clubs, sticks or the like for golf or other purposes, comprising a socket member, weighting means adapted to be carried within said socket member, and a resilient tongue in the wall of the socket member to press upon the weighting means within 55 the socket member.

In testimony whereof I have signed my name to this specification in the presence of two subscribing witnesses.

PERCY GORDON ECKEESLEY DANIEL.
